**COMBINATION AUXILIARY BRIDGE AND NOSE
PAD ATTACHMENT FOR A SPECTACLE FRAME
FRONT**

Vertis A. Downie, Brooklyn, and Harry Weissman, Great Neck, N.Y. (both % Paramount Optical Mfg. Corp., 60-06 39th Ave., Woodside 77, N.Y.)

Filed Jan. 30, 1964, Ser. No. 78,436

Term of patent 14 years

(Cl. D57—1)

Fig. 1

Fig. 2

Fig. 3

Fig. 4

Fig. 5

FIG. 1 is a top plan view of a combination auxiliary bridge and nose pad attachment for a spectacle frame front showing our new design as it appears attached to a frame front.

FIG. 2 is a front elevational view thereof.

FIG. 3 is a top plan view of the combination auxiliary bridge and nose pad attachment.

FIG. 4 is a front elevational view of FIG. 3.

FIG. 5 is a side elevational view of FIG. 3.

The dominant features of our design reside in the portions shown in full lines.

We claim:

The ornamental design for a combination auxiliary bridge and nose pad attachment for a spectacle frame front, substantially as shown and described.
